UNITED STATES PATENT OFFICE.

JOSEPH WALTER ADAMS, OF SANTA ANA, CALIFORNIA, ASSIGNOR OF ONE-HALF TO DANIEL M. FRAWLEY, OF SANTA ANA, CALIFORNIA.

WINDOW-SCREEN.

SPECIFICATION forming part of Letters Patent No. 736,919, dated August 25, 1903.

Application filed March 31, 1903. Serial No. 150,428. (No model.)

To all whom it may concern:

Be it known that I, JOSEPH WALTER ADAMS, a citizen of the United States, residing at Santa Ana, in the county of Orange and State of California, have invented a new and useful Window-Screen, of which the following is a specification.

My invention relates to window-screens, and has for its objects to produce a device of this character which is simple of construction, efficient in operation, one in which the screen-sections are susceptible of a slight relative longitudinal movement which admits of their ready manipulation for insertion into the window-casing, and one in which the sections will automatically expand longitudinally for proper seating within the sash-retaining guides.

To these ends the invention comprises the novel details of construction and combination of parts more fully hereinafter described.

In the accompanying drawings, Figure 1 is a side sectional elevation of a screen constructed in accordance with my invention, illustrating the sections in their relatively extended position. Fig. 2 is a similar view illustrating the parts in their contracted position. Fig. 3 is a detailed section on the line 3-3 of Fig. 1.

Referring to the drawings, 1 indicates one section of the screen, herein termed the "main" section, and 2 the companion section, which I term the "secondary" section. The frame of the main section consists of a top bar 3, a bottom bar 4, and end bars 6, as does also the frame of the secondary section. The frame of each section is provided with and sustains the usual reticulated material 7.

8 and 9 indicate a pair of supplemental frame-bars which are secured to the end bar 6 of the main screen-section in any suitable manner. These supplemental frame-bars are mounted one at each side of the screen-section, are disposed transversely of the same, and project a slight distance beyond the top frame-bar 3 for the purpose presently explained. The supplemental frame-bars 8 and 9, which are spaced one from the other a distance equal to the thickness of the frame-bar 6 in order to receive between them for sliding movement the end bar 6 of the secondary

section for the purpose hereinafter explained, each consists of an inner board 10 and an outer board 11, equal in dimensions and lying one upon the other. The inner face of each of the supplemental bars 8 and 9 is provided with a pair of main grooves 12 and 13, which are disposed transversely of the bars and terminate short of the outer edge of the same, where they are joined each by a supplemental angularly-disposed entrance-groove 14 15, which forms a continuation of the main groove and extends to the outer edge of the bar. These grooves are situated one near each end of each of the bars and receive for sliding movement transverse pins 16 17, which project laterally from opposite sides of the end bar 6 of the secondary screen-section 2. Thus the screen-sections are adapted for attachment one to the other and for a relative longitudinal movement, as will be readily understood. The inner faces of the supplemental bars are further provided with transverse recesses 18 19, which receive, respectively, springs 20 21. These springs are situated one adjacent to either end of the supplemental bars and are normally expanded, thus tending to force the secondary screen-section away from the main section to extend the screen as a whole longitudinally. It will be apparent, however, that the screen-sections are susceptible of a movement for compressing the springs and shortening the screen as a whole longitudinally. In order to permit of the ready manipulation of the screen-sections for compressing the springs, there is provided a finger-piece 22, secured in any suitable manner to the end bar 6 of the secondary screen-section. This finger-piece is preferably in the form of strap metal secured at its outer end to the frame-bar and extending inward a suitable distance, with its inner end bent at right angles to form a horizontal finger adapted to be grasped by the operator while manipulating the parts. It is to be noted that the springs 20 21 are seated at their ends in suitable sockets 23 24, formed, respectively, in the adjacent end faces of the bars 6. Further, it will be noted that the outer ends of the main grooves 12 13 terminate in abrupt shoulders 25, which constitute stops against which the pins 16 17 abut for limiting the outward lon-

gitudinal movement of the secondary section 2.

In practice the sections are assembled by inserting the pins 16 17 through the entrance-grooves into the main transverse grooves, as will be readily understood. In this manner the screen-sections are movably connected, and if it is desired to insert the screen into a window the finger-piece 22 is grasped and manipulated for forcing the secondary section longitudinally inward toward the main section against the action of the springs, and after the screen has been properly inserted the springs will, upon release of the finger-piece, automatically extend the sections to cause the screen to firmly engage the window-casing within the sash-guides. When the screen is in the window, the weight of the latter will be borne wholly by the supplemental frame-bars, owing to their being extended slightly above the top frame-bars of the screen, as hereinbefore mentioned.

From the foregoing it will be seen that I produce a simple and efficient device which is admirably adapted for the attainment of the ends in view; but it is to be understood that I do not limit myself to the details herein shown and described, inasmuch as various minor changes may be made therein without departing from the spirit or scope of my invention. For example, the supplemental bars may each consist of a single board and instead of the spiral springs herein shown being employed leaf-springs may be substituted, and, in fact, a single spring may be used instead of a pair of springs, as herein described.

Having thus described my invention, what I claim is—

1. In a screen, the combination with a screen-section having a frame-bar provided with grooves, of a companion screen-section provided with devices for engaging the grooves, and a spring interposed between the sections. 40

2. In a screen, the combination with a pair of screen-sections, of spaced supplemental frame-bars associated with the main section and provided with grooves, devices carried by the secondary screen-section for engaging with said grooves, and a spring interposed between the screen-sections. 45

3. In a screen, the combination with a main screen-section, of a pair of spaced supplemental bars associated therewith and provided with grooves shouldered to form stops, a secondary screen-section, devices carried thereby for engagement with the grooves, and a spring interposed between the screen-sections. 55

4. In a screen, the combination with a screen-section having a frame provided with grooves, of a companion screen-section provided with devices for engaging the grooves, a finger-piece associated with the latter section, and a spring interposed between the spring-sections. 60

In testimony that I claim the foregoing as my own I have hereto affixed my signature in the presence of two witnesses.

JOSEPH WALTER ADAMS.
